UNITED STATES PATENT OFFICE.

HENRY L. FISHER, OF RICHMOND, VIRGINIA.

SIGNATURE-GATHERING MACHINE.

1,194,987.

Specification of Letters Patent. Patented Aug. 15, 1916.

Application filed April 16, 1913. Serial No. 761,517.

To all whom it may concern:

Be it known that I, HENRY L. FISHER, a citizen of the United States, residing at Richmond, in the county of Henrico and State of Virginia, have invented certain new and useful Improvements in Signature-Gathering Machines; and I do hereby declare the following to be a full, clear, and exact description of the invention, such as 5 will enable others skilled in the art to which it appertains to make and use the same.

This invention relates to new and useful improvements in signature gathering machines and as its principal object aims to 15 provide means for collecting the signatures, conveying them from the signature boxes into the receiving trough, and imposing them one against the other in assembled order.

20 A further object resides in the provision of means for permitting a number of signature piles to be placed in the machine at the same time, and in position where they may be fed under the gathering apparatus as 25 each pile is exhausted.

A still further object resides in the provision of improvements controlled by the gathering mechanism for automatically jogging the signature from the gathering 30 device down onto the conveying apparatus.

A yet further object is to provide a novel form of guide for the gathering device which will act to automatically direct the gatherers into the proper position of engagement with the signatures.

35 A still further object resides in the provision of means for gathering the signatures from their respective boxes and depositing them on the conveyer in the proper order.

40 The above and additional objects are accomplished by such means as are illustrated in the accompanying drawings, described in the following specification and then more particularly pointed out in the claims which 45 are appended hereto and form a part of this application.

With reference to the drawings, wherein I have illustrated the preferred embodiment 50 of my invention as it is reduced to practice, and throughout the several views of which similar reference-numerals designate corresponding parts: Figure 1 is a side elevation. Fig. 2 is an end elevation taken at the forward end of the machine. Fig. 3 is a section on the line 3—3 of Fig. 1. Fig. 4 is a 55 detail view of the gathering arms indicating

by dotted lines the various positions taken by the arms in gathering a signature from its box and depositing it on the conveyer. Fig. 5 is a section on the line 5—5 of Fig. 1, 60 illustrating in detail the means employed in jogging the signatures from the gathering arms; and Fig. 6 is a detail view of one of the gathering arms. Fig. 7 is a detail view of the ratchet connection. 65

Proceeding now to the description of the drawings, the preferred embodiment of this invention includes four main elements, the gathering device, the conveyer signature boxes and guides, the jogger for releasing 70 the signatures from the gathering arms and depositing them on the conveyer, and the rotor for depositing the signatures in the receiving trough.

Gatherers.—Taking up these elements in 75 the order named, the gathering mechanism of this invention includes an actuating apron 1 mounted for rotation around terminal sprocket wheels, one of which is illustrated at 2. The sprocket wheels 2 are journaled between the vertical legs 4 and 5, and 6 and 7 of the main supporting frame. The wheels 2 mesh with the links of a chain 3 secured to the inner face of the apron. This supporting frame is preferably formed of 80 angle iron and further consists of the longitudinal beams 8 and 9, 10 and 11, and 12 and 13, arranged in alined pairs as indicated, and connecting the vertical legs 4 and 6, 5 and 7. The lower terminals of the 85 vertical beams may be bolted or otherwise secured to the floor as at 14. The apron 1 may be made of any suitable material, although spaced laterally extending hingedly connected wooden slats are preferred. This 90

apron member is arranged for movement over the lateral leg portion of the angle iron beams 10, 11, 12 and 13, as will be observed by reference to Fig. 2. To the apron 1 are attached the gathering arms of this device. The gathering arms are arranged in pairs as indicated at 15 and 16, and consist essentially in a bar member hinged at its upper terminal to the apron 1 as indicated at 17, and having its lower free terminal bifurcated to produce the fork tines 18. One tine of each gathering arm carries a plurality of pins 19 provided to engage the signatures and carry them from their boxes, as will be hereinafter described. 105

Conveyer.—Taking up as next in order the conveying apparatus, this feature of the 110

invention consists essentially in an apron 20 mounted for movement around pairs of terminal sprocket wheels, one pair of which is illustrated at 21. The sprocket wheels 21 are journaled between the vertical legs 4 and 5, and 6 and 7, and mesh with the links of the chains A and B. On the journaled shaft 23 a gear wheel 24 is arranged to mesh with a gear wheel 25 which is in turn operatively connected to a gear wheel 26 of the shaft of the sprocket wheels 2 by a counter-gear 27 for the purpose of permitting the aprons 1 and 20 to be driven from a common power source. The apron 20 is mounted to permit the movement of its upper portion immediately beneath the longitudinal beams 8 and 9, as illustrated in Fig. 2. Journaled in suitable brackets 28 of any suitable type, carried on the vertical legs 6 and 7, and extending forwardly therefrom is a pair of hubs 29, carrying radially extending arcuate fingers 30, adapted to be driven simultaneously to receive the signatures as they drop from the forward end of the apron and to subsequently deposit them in the signature receiving trough designated as an entirety by the numeral 32. A ratchet wheel 31' is secured to one end of the shaft 46' and journaled upon the shaft 46' is a rod 48 having a dog 49 pivoted thereto, and adapted to normally engage the ratchet wheel 31'. Pivotaly connected to the free end of the rod 48 is a connecting link 49' which is pivotally connected to the crank arm 31 and is rigidly mounted on the shaft 46, whereby a well-known ratchet mechanism is provided to rotate the fingers 30 according to the movement of the belt 20.

Signature boxes and guides.—Assuming that the machine is to be employed for collecting the signatures of a book composed of three sections, there has been illustrated in the drawing three signature boxes 33, 34 and 35, containing respectively the first, second and third signatures. As illustrated in Fig. 2, the signature boxes are formed with an open front. Connecting the longitudinal beams 8 and 9 are three pairs of angle iron supporting runners 36 for the signature boxes. It will be observed from the foregoing that the signatures composing the first section of the book may be arranged in the box 33 in two or more piles to permit the signature box to be fed through the machine, first bringing the pile of one of the boxes under the gathering arms, then the pile in another box, when the pile in the first box has been exhausted. Each rear supporting runner 36 carries a pair of downwardly turned substantially arcuate deflecting fingers 37, carried rearwardly of the signature compartments and mounted in spaced relation to each other. These fingers 37 are provided for the purpose of deflecting the arms 15 upwardly, as the apron

rotates and moves the arms into the position indicated in Fig. 1. It will be noted that the finger 37 will pass between the tines 18 of the arms 15 as the apron progresses to bring the free end of the arm toward the upper end of the signature boxes. Referring now more particularly to Fig. 4, it will be observed that as each arm 15 passes over its guide 37 it will drop down into the signature box, as illustrated by dotted lines at 75 38. By reason of the sudden fall of the arm, the pins 19 will pierce a portion of the signature leaves with sufficient force to engage the signature and draw it from the box as the apron progresses, as illustrated at 80 39 in Fig. 4.

Strippers.—It is apparent that it will require some automatic device to release the signature from the pins 19. In order to accomplish this result, this invention employs 85 a stripper 40 pivotally connected at one terminal to the horizontal leg 41 of an L-shaped standard 42 secured at its lower terminal to a runner 36. One of these members 42 is provided for each signature box, 90 and is mounted approximately mid-way between the longitudinal beams 8 and 9. In the preferred form of this invention, the arms 15 and 16 are hinged to a cross bar 43 carried by the apron 1 and to the lower portion of the cross bars is secured an L-shaped supporting bracket 44, the lateral leg of which is arranged to engage the stripper 40 and to swing it upwardly on its pivot as the apron progresses. As the strippers 40 100 are released from the supporting bracket 44, they will of course swing downward and strike the signature mid-way between the two arms 15 and 16. The movement imparted to the signature by the stripper 40 will 105 be sufficient to disengage the signature from the pins and to force it down upon the apron 20. The stripper 40 after striking the signature swings back into its normal position, and by contact with the signatures 110 rearranges them in their normal position, acting to return any signature which may have been loosened by the action of the gathering arm into its previous position in the signature box. After returning to its 115 normal position as indicated, in Fig. 4, the stripper is ready to be swung forward by the supporting bracket 44 of the next pair of gathering arms. The shaft 46 of the roller 21 may be provided with a belt wheel 120 47 by which operative connection may be had with a motor or other suitable power source.

In reduction to practice, I have found that the form of my invention, illustrated in 125 the drawings and referred to in the above description, as the preferred embodiment, is the most efficient and practical; yet realizing that the conditions concurrent with the adoption of my device will necessarily vary, 130

I desire to emphasize the fact that various minor changes in details of construction, proportion and arrangement of parts may be resorted to, when required, without sacrificing any of the advantages of my invention, as defined in the appended claims.

What is claimed is:

1. A signature gatherer including a main supporting frame, an upper and lower apron supported therein and mounted in parallel spaced relation to each other, a plurality of removably mounted signature boxes arranged between the aprons, a plurality of separator arms hingedly secured to the upper apron, the free ends of said separator arms adapted to engage the top signature of each pile in succession and remove the signature from its box, means for disengaging the signatures from said separator arms subsequent to their withdrawal from said signature boxes and causing them to be dropped upon the lower of said aprons, means for rotating said aprons, a receiving trough disposed adjacent one terminal of the lower-most apron and means for conveying the signatures from the lower apron to said receiving trough.

2. A signature gathering machine including a main supporting frame, a pair of rotating aprons mounted therein and in parallel spaced relation to each other, means for rotating said aprons, a plurality of signature boxes removably arranged in said main frame and disposed between said aprons, separator arms hingedly secured to said upper apron, the free terminals of said arms adapted to engage and remove the top signature of each pile in succession during the rotation of said upper apron, means for guiding the signature arms into operative position in said signature boxes, means automatically operated by said upper apron for removing the signatures from said separator arms and causing them to be dropped on said lower apron, a receiving trough disposed adjacent one terminal of the lower apron and means for conveying the signatures from the lower apron to said receiving trough.

3. A signature gathering machine including a main supporting frame, a pair of rotating aprons mounted in said frame and in spaced superposed relation to each other, means for rotating said aprons, a plurality of separator arms arranged in pairs on said upper apron, a plurality of signature boxes mounted on said frame between said apron, guide members carried by said signature boxes for deflecting the separator arms upwardly and directing them into operative position, means to disengage the signatures from the separator arms and for causing them to be dropped upon the lower apron, said means including a pivotally mounted stripper arm and means carried by said

upper apron for automatically lifting said stripper arms and releasing them after the operation of said separator arms.

4. A signature gathering machine including a main supporting frame, an upper and lower apron rotatably mounted within said frame, means for rotating said aprons, a plurality of signature boxes disposed between said aprons and removably mounted in said frame, a plurality of separator arms hingedly secured in pairs to said upper apron, said arms each consisting of a body portion having its lower terminal arcuately bent and bifurcated to produce tines, a plurality of pins carried by said tines, guide members carried by each of said signature boxes, a receiving trough disposed adjacent one end of said lower apron, the free terminals of said separator arms adapted to engage the top signature of each pile in succession and remove the signature from said boxes, means for removing the signatures from said separator arms and causing them to be dropped upon said lower apron and means for conveying the signatures from said lower apron into said receiving trough.

5. A signature-gathering machine including a main supporting frame, a pair of rotating aprons mounted in said frame and in parallel spaced relation to each other, means for rotating said aprons, a plurality of signature boxes removably mounted in said frame, a plurality of separator arms hingedly connected with the uppermost of said aprons, the free ends of said separator arms adapted to engage the top signature of each pile in succession and remove the signatures from the boxes and causing them to be dropped on said lower apron, a receiving trough disposed adjacent one terminal of said lower apron within the frame, means for conveying the signatures from said lower apron into said receiving trough comprising a pair of hub members, a rotatable shaft for said hub members, said shaft being operatively connected to the driving means for said aprons, and a plurality of radially extending arcuate fingers carried by each of said hub members.

6. A signature gathering machine including a main supporting frame, a pair of rotating aprons mounted in said frame in parallel superposed relation to each other, means for rotating said aprons, a plurality of signature boxes removably mounted in said frame, a plurality of separator arms hingedly connected with the uppermost apron, the free ends of said separator arms adapted to engage the top signature of each pile in succession and remove the signatures from the boxes, a stripper arm adapted for engagement with the signatures carried by the separator arms to remove and causing them to be dropped upon the lower apron, a signature-receiving trough disposed adj-

- cent one end of said lower apron and means for conveying the signatures from the lower apron to said receiving trough comprising a pair of hub members, a rotatable shaft for 5 said hub members, said shaft operatively connected with the driving means for said aprons, and a plurality of radially extending arcuate fingers for each of said hub members.
- 10 7. A signature gathering machine, comprising a pair of spaced aprons, of means for rotating said aprons, a plurality of signature boxes slidable transversely between said aprons, supporting means for 15 said signature boxes, signature-removing means carried by one of said aprons, and means carried by said signature boxes for removing the signatures from said last-named means and causing them to be 20 dropped upon the other of said aprons.
8. In a signature gathering machine, the combination with a pair of spaced aprons of means for rotating said aprons, a plurality of signature boxes disposed between 25 said aprons, means for removably supporting said signature boxes extending transversely of said aprons, signature separating arms hingedly secured to one of said aprons, means carried by each of said signature 30 boxes for removing the signatures from said separating arms and causing them to be dropped upon the other of said aprons and brackets carried by said first-mentioned apron for actuating said last-named means.
- 35 9. In a signature gathering machine, the combination with a frame work of a pair of spaced aprons rotatably mounted there-
- on, means for rotating said aprons, a pair of spaced runners mounted transversely of and between said aprons and upon said 40 frame, a plurality of signature boxes slidably mounted upon said runners, a plurality of signature-separating arms hingedly secured to one of said aprons and adapted to engage and remove the top signature of 45 each pile from the boxes, means carried upon the free terminals of each of said arms for removing the signatures from said signature boxes, means carried by each of said signature boxes for removing the signatures 50 from said last-named means and causing them to be dropped upon the other of said aprons and a plurality of L-shaped brackets secured to said first named apron for actuating said last named means. 55
10. In a signature gathering machine, the combination with a pair of rotatable aprons of means for rotating said aprons, a plurality of signature boxes disposed between said aprons, a plurality of signature-separating arms hingedly secured to one of said aprons, means for removing the signatures from 60 said signature-separating arms and causing them to be dropped upon the other of said aprons, a receiving trough disposed adjacent said last named apron and means for conveying the signatures from said last named apron into said receiving trough. 65
- In testimony whereof I affix my signature in presence of two witnesses.
- HENRY L. FISHER.
